UNITED STATES PATENT OFFICE.

THOMAS H. SEELY, OF MALDEN, MASSACHUSETTS, ASSIGNOR TO UNITED SHOE MACHINERY CORPORATION, OF PATERSON, NEW JERSEY, A CORPORATION OF NEW JERSEY.

METHOD AND MEANS FOR DETERMINING THE SHAPE OF MOLDS.

Application filed July 8, 1918. Serial No. 243,986.

To all whom it may concern:

Be it known that I, THOMAS H. SEELY, a citizen of the United States, residing at Malden, in the county of Middlesex and State of Massachusetts, have invented certain Improvements in Methods and Means for Determining the Shape of Molds, of which the following description, in connection with the accompanying drawings, is a specification, like reference characters on the drawings indicating like parts in the several figures.

This invention relates to the art of producing such implements as molds, of which those used in making leggings furnished an example.

One of the methods of manufacturing leggings consists in pressing sheets of leather or other material between a trough-shaped female mold and a co-operating male mold, the transverse elements of the curved surfaces of which should be as nearly as possible partial developments of corresponding sections of the object, in the present instance the calf and ankle portions of a leg, over which the article molded is designed to fit. An object of this invention is to provide for the accurate determination of the shape of these molds and for their production.

A feature of the invention is found in the method by which the shape of the mold is determined by generating its elements through the travel of a form. This form preferably corresponds to or has the general contour of the object with which the article to be molded is to co-operate, and is herein illustrated as a leg form. The operation may be accomplished by the steps of rotating and revolving the form so that an envelope of roulettes is generated from one of its elements. Such envelopes may then be combined to form a complete mold. The rotation is preferably through 360 degrees, while the revolution is conveniently through a less angle, as 180 degrees.

The mold, in the illustrated embodiment of the invention, is made up of sections, in which case a feature of the invention consists in tracing the mold elements upon successive sections and then assembling the sections. As these steps are most readily

performed, each section would contain at least one correct element of the mold, this lying in the plane in which the tracing is made, though other elements of the section may depart from the proper shape. Therefore, the assembled sections may be further operated upon to bring the portions intermediate the true elements to the contour sought.

As a further feature, the opposite parts of co-operating molds are produced simultaneously by dividing sections of material. This results in male and female mold portions at opposite sides of the line of division. Then the sections of the respective molds may be assembled and brought throughout to the desired shape. To give uniform pressure between the mold portions, the material removed in dividing them preferably does not exceed in thickness that of the article to be molded, and the total thickness of material taken from the two portions is substantially that of said article.

Additional features concern an apparatus by which the steps of the method previously outlined may be performed, and in which a form support is moved to cause elements of the mold surface to be generated by a form carried thereby and the shape of such elements recorded. As herein illustrated, this recording means includes a member variable in position to enable successive elements to be traced. In the production of molds for leggings, a leg form is employed, the recording means co-operating therewith at different points between the ankle and calf portions. As the preferred embodiment of the apparatus, I have shown the form support as including a carrier and a form holder rotatable thereon. The recording means is preferably mounted on the carrier, having a marking member for tracing the generated curves and a contact member movable toward and from the form support and adjustable along said support.

Other features will hereinafter appear, reference being had to the accompanying drawings, in which—

Fig. 1 is a top plan view of one form of my improved apparatus;

Fig. 2 is an end elevation thereof looking from the left in Fig. 1;

Figs. 3 and 4 are details in perspective of portions of the recording mechanism;

Fig. 5 illustrates diagrammatically the manner in which the generated curve is traced; and

Fig. 6 is a central vertical section through assembled sectional mold portions after the separate sections have been divided.

A supporting frame is shown consisting of a base 10 and opposite vertical end pieces 12 and 14. In using the apparatus to determine the shape of successive mold sections, the end piece 12 may serve as a receiver for said sections, one at a time. For this purpose it is made in the form of an open frame, in which may be placed rectangular plates or thin blocks W of material, as wood, from which the mold or pattern portions are to be made. These are held in place by some such securing means as buttons 16 and have the inner face toward the opposite end piece 14 exposed for the tracing operation.

Pivoted at 18 upon an arm 20 depending from the upper portion of the end piece 12 and at 22 in an upright 24 rising from the end piece 14 is a carrier member 26 of a form support. This carrier member is U-shaped, having arms 28 extending upon the opposite side of the pivots from the body of the U, there being secured to the closed portion of the carrier a handle 30 by which the support may be turned through an angle, in the present instance of 180 degrees. The handle is preferably of such weight as to tend to counterbalance that of the support and form. Mounted to rotate in the arms of the carrier is a form holder including a spindle 32 having a flanged head 34 of somewhat enlarged diameter and arranged to turn in an opening in the left-hand arm of the carrier, as viewed in Fig. 1, and a reduced end portion 36 rotatably journaled in a smaller opening in the opposite arm. Contacting with the inner side of the head 34 is a collar 38 having a bow 39 contacting with the enlarged head 34 and carrying at one edge of its periphery a gear 40, which is shown as of the pin type. At the opposite side of the collar is a projection 42 extending parallel to the spindle. The extremity of the spindle opposite the head is threaded at 44 to receive a nut 46 carrying a hand wheel by which it may be turned. At 48 appears a form corresponding generally to the shape of the object to which the molded article is to be applied. As the apparatus disclosed is for use in producing molds for manufacturing leggings, a leg form including calf and ankle portions is employed. In placing the form upon the holder, the spindle is withdrawn from the arms and the collar, form and nut held alined with the openings in the arms. The spindle is

then introduced through these openings and the nut turned upon the thread 44, the collar projection 42 entering a bore in the ankle portion of the form to compel its rotation with the gear 40. The screwing up of the nut against the calf end of the form forces it against the collar 38, thus forcing the boss 39 against the shoulder formed by the enlarged head 34. The width of the head 34 being somewhat greater than the thickness of the arm 28, the spindle is free to turn in the openings in the arms 28. The purpose of the boss 39 is to provide adequate spacing between the arm 28 and the adjacent gearing. At this time the gear 40 meshes with a segmental pin gear 50 carried upon the inner face of the end piece 14 of the frame, the result of this engagement being that when the carrier is turned to revolve the form about the pivots 18 and 20, the spindle and form are simultaneously rotated. The diameter of the pitch circle of the gear 50 is shown substantially twice that of the gear 40, and the pitch circle of the gear 40 therefore passes substantially through the axis 18-22.

On the carrier 26 is mounted mechanism for tracing or recording the curves generated by the movement of the form. In separated arms 52, 52, extending from the closed portion of the U-carrier beneath the spindle to the opposite side of the form, are pivot pins 54 threaded through the arm and having conical ends to rotatably support a bar 56. This bar has at the end toward the block W held in the end piece 12 an arm 58 provided with a marking member, conveniently in the form of a wheel 60 turning upon a screw 62. The sharp edge of this wheel bears against the face of the block W, so that it indents said block as it moves over it. Arranged to slide upon the bar 56 is a carrier block 64 having a contact wheel 66 turning upon a screw 68. In a bore in this block is a conical-ended latch member 70 forced by a spring 72 toward the top of the bar 56 to engage one or another of a series of depressions 74 and thus temporarily hold the contact wheel in definite longitudinal relation to the form. The wedge-shaped tracing edge of the wheel 60 is in alinement with the contact edge of the wheel 66, considered in a direction parallel to the axis of the holder spindle 32. A spring 76 extending between one of the arms 52 and the arm 58 tends to rock the bar 56 about its pivots to hold the contact wheel 66 constantly against the form.

The operation of the apparatus in carrying out the method of this invention may be understood by a consideration of Figs. 5 and 6 of the drawings. A form 48 corresponding to the size of the legging for which molds are to be made is fixed in the holder. The receiver in the end piece 12 is

supplied with one of the section blocks W with its inner face against the edge of the wheel 60 , and the contact member is positioned with its latch in a particular one of the depressions 74 , say at one extremity of the form. Now, as the handle 30 is swung from its position illustrated in Figs. 1 and 2 through 180 degrees, the form is revolved about the pivots 18 and 22 , this axis being indicated at a in Fig. 5, through an equal arc, while by the gearing $40, 50$, the pitch circles of which are shown at b and c (Fig. 5), it is rotated a full turn about the axis of the spindle 32 which moves in the path d . The pitch diameter of the circles c and b have been described as having a ratio of substantially $2:1$. This insures that the length of the arc c be equal to the circumference b so that a complete rotation of the form (from the standpoint of the arc c) will result from the revolution of the form through the angle subtended by the arc c at the center a , which in the construction shown in Fig. 5 is 180° . This construction has been found convenient in practice, but is not necessary in order to carry out the present invention in its broadest aspect. It is necessary only that that part of the circle c which is used shall be equal to the complete circumference b . If, for example, the distance $22-32$ were increased while the circle c remained unchanged, the circle a would be smaller and would no longer pass through the point a , and its circumference would be rolled out in less than a semi-circumference of the circle c , and the form would have to revolve only through the corresponding angle. Such a construction is shown in Fig. 2. This method of generating forms is of particular value in making molds for articles not having extreme changes in curvature, such as leggings or puttees. It amounts to the making of a partially developed mold, that is, a mold which has been partially flattened out toward a plane, this flattening involving, in general, some distortion. The making of molds under the previously existing practice has been very expensive, involving accurate molding or pattern reproduction. In the case of articles whose surfaces are so shaped as to be partially developable without prohibitive distortion, the present method is of great importance.

The angle of revolution adopted (as the word is herein used) depends upon the amount of development that is permissible, in view of the distortion introduced thereby. The advantages of the invention could be secured in some instances by making the circle c a straight line, and rolling a form along it. This amounts to a zero revolution and is one extreme; accurate pattern reproduction, which corresponds to revolution and rotation of 360° each, being the

other. The more revolution there is per 360° of rotation, the more accurate the reproduction is. Obviously as a practical mechanical matter a close approach to 360° revolution is not possible, as the a and c ⁷⁰ circles are then so close together that the mechanical parts will not clear in movement. The drawing illustrates an intermediate condition. The wheel 60 revolves with the form, and, under the influence of the contact wheel 66 , varies as to its distance from the axis of revolution an amount depending upon the contour of the transverse section of the form which is at that time, rotating beneath the contact wheel. ⁷⁵ There is consequently generated and traced by the wheel 60 an envelope of all the roulettes generated by the points of this transverse element, the curve e in Fig. 5 being such a development of the maximum ⁸⁰ circumference of the form. The curve c can be regarded as a directrix for the generation of the roulettes and of their envelope, and the curve a may be called the rolling perimeter of the form 48 . The ⁸⁵ generation of the envelope e , of the roulettes generated by the points of the perimeter of the form 48 which is being treated to form the corresponding envelope e , can be regarded as the combination of the small ⁹⁰ corresponding portions of adjacent roulettes which closely approximate the envelope. That is, those portions of two "adjacent" roulettes which have a common tangent with the envelope in that vicinity, can be ⁹⁵ regarded as combined or placed end to end to form the corresponding portion of the envelope.

The envelopes, when obtained, are cross-sections of the resulting mold formed by planes perpendicular to the axis 32 , and corresponding to the settings of the block 64 along the bar 56 . The mold is formed by assembling these cross-sections in the proper relation, in order. Upon other ¹⁰⁵ blocks W like curves are similarly traced for successive settings of the contact member 66 along the bar 56 . The blocks of material are then divided, as by sawing at f (Fig. 6), along the indicated lines in a direction at right angles to the faces bearing the curves and the corresponding portions assembled and secured together to furnish an approximation of the respective male and female halves A and B of the mold. It will be seen that each section of each mold portion will contain at least one transverse element of the true contour, corresponding to the element of the form ¹¹⁰ which passes beneath the contact wheel. Material is then removed from the opposed mold surfaces at the intermediate elements until the desired shape is attained, as shown by the lines g and h in Fig. 6. To obtain ¹¹⁵ proper co-operation between the mold por-

tions with uniform pressure over the entire surface of the article molded, the thickness of material removed in dividing the portions should not exceed the thickness of said article. Preferably, the total width of the space formed by both dividing and finally shaping the surfaces is substantially equal to the thickness of the article. If the amount removed is less, there will be an excessive pressure at the outer edges of the mold; if greater, there will be too heavy pressure at the center.

In this description and the appended claims, I have referred to the production of molds by the present method or have employed language indicating that a mold directly results. While for certain classes of work involving the application of relatively light pressure this course may be feasible with molds of wood, and while the same steps might be utilized to form molds of metal, with the latter material it is preferable to employ the implement made through the application of my method to wood sections as patterns from which metal molds are cast, and it is to be understood that such a procedure is covered by the claims of this invention.

Having fully described my invention, what I claim as new and desire to secure by Letters Patent of the United States is:

1. That improvement in methods of determining the shape of a mold which consists in generating a linear element of the mold by combining portions of the paths of points on the periphery of a form as it rolls along a directrix, the portions combined being, in order, those portions of the paths corresponding to pairs of adjacent points along the curve which have a common tangent, and arranging such linear elements in order in parallel planes to make the mold surface, and combining such linear elements of the form.

2. That improvement in methods of determining the shape of a mold by generating a curved element of the mold by adding end to end, in order selected portions of the paths of the points taken in the same order on a corresponding element of a form, as the form rolls along a directrix.

3. That improvement in methods of determining the shape of a mold by generating a curved element of the mold by placing end to end, in order, selected portions of the paths of the points taken in the same order on a corresponding element of a form, as the form rolls along a directrix, the directrix being curved over an arc of substantially less than 360° while of such length as to cause the form to roll through an angle of 360° along it.

4. That improvement in methods of determining the shape of a mold by generating a curved element of the mold by adding

end to end, in order, selected portions of the paths of the points taken in the same order on a corresponding element of a form, as the form rolls along a directrix of semi-circular form and of length equal to the 70 rolling periphery of the form.

5. That improvement in methods of determining the shape of a mold which consists in generating roulettes of points on the periphery of a form, forming the envelope of these roulettes and using this envelope as an element of the mold.

6. That improvement in methods of determining the shape of a mold which consists in generating roulettes of points on an 80 element of a form, forming the envelope of these roulettes, and forming the mold surface by assembling the roulettes corresponding to successive elements of the form in order.

7. That improvement in methods of determining the shape of a mold for leggings which consists in rolling a legging-like form along a directrix, recording the envelope of the roulettes generated by points on an element of the mold, and combining these roulettes as elements of the mold surface.

8. That improvement in methods of determining the shape of a mold for leggings which consists in rolling a legging-like form 95 along a curvilinear directrix, recording the envelope of the roulettes generated by points on an element of the mold, and combining these roulettes as elements of the mold surface.

9. That improvement in methods of determining the shape of a mold for leggings which consists in rolling a legging-like form along a semi-circular directrix, recording the envelope of the roulettes generated by points on an element of the mold, and combining these roulettes as elements of the mold surface.

10. That improvement in methods of determining the shape of a mold for leggings which consists in rolling a legging-like form along a semi-circular directrix, the length of the semi-circle being substantially equal to the rolling perimeter of the form, recording the envelope of the roulettes generated by points on an element of the mold, and combining these roulettes as elements of the mold surface.

11. The method of producing co-operating molds, which consists in dividing successive sections of material to furnish adjacent portions of opposed mold surfaces, and assembling the sections.

12. The method of producing co-operating molds, which consists in tracing elements of a mold on successive sections of material, dividing the sections to furnish adjacent portions of opposed mold surfaces, and assembling the sections.

13. The method of producing co-operat-

ing molds, which consists in dividing successive sections of material to furnish surfaces containing elements of opposed mold surfaces, assembling the sections, and bringing the assembled sections to the desired shape.

14. In an apparatus for determining the shape of molds, a form support operable to cause elements of a mold to be generated by 10 a form carried on the support, and means for recording said elements.

15. In an apparatus for determining the shape of molds, a form support movable to cause elements of a mold to be generated by 15 a form carried on the support, and means variable in position with respect to the form for separately recording said elements.

16. In an apparatus for determining the shape of molds for leggings, a movable leg 20 form, and means for recording arbitrarily selected transverse contours generated by the movement of the form.

17. In an apparatus for determining the shape of molds for leggings, a movable leg 25 form, and means variable in position with respect to the form for separately recording successive contours between the calf and ankle portions generated by the movement of the form.

18. In an apparatus of the class described, 30 a rotatable carrier, a form holder mounted on the carrier, means for rotating the holder, and recording means for co-operation with a form carried on the support.

19. In an apparatus of the class described, 35 a rotatable carrier, a form holder mounted on the carrier, means for rotating the holder, and recording means mounted on the carrier to move toward and from the holder for co-operation with a form carried on the support.

20. In an apparatus of the class described, 40 a rotatable carrier, a form holder mounted on the carrier, means for rotating the holder, and recording means including an element adjustable in position along the holder for co-operation with a form carried on the support.

21. In an apparatus of the class described, 45 a rotatable carrier, a form holder mounted on the carrier, means for rotating the holder, and recording means including a member for contact with a form carried on the support and a marking member.

22. In an apparatus of the class described, 50 a rotatable carrier, a form holder mounted on the carrier, means for rotating the holder, and recording means including a member for contact with a form carried on the support and a marking member, the contact

portions of said members lying in a line parallel to the axis of rotation of the holder.

23. In an apparatus for determining the shape of successive sections of molds, retaining means for the mold sections, a form support movable to cause elements of a mold to be generated by a form carried on the support, means for recording the shape of said elements including a member movable along the support, and means constructed and arranged to fix the position of the member in accordance with the thickness of the mold sections.

24. In an apparatus of the class described, 65 a rotatable carrier, a form holder rotatable on the carrier, means for communicating the movement of the carrier to the holder, and marking means arranged for actuation by a form carried on the support.

25. In an apparatus of the class described, 70 a rotatable carrier, a form holder rotatable on the carrier, gearing acting in the rotation of the carrier for turning the form holder through a greater angle than that through which the carrier travels, and marking means arranged for actuation by a form carried on the support.

26. In an apparatus of the class described, 75 a frame, a carrier movable thereon, a form holder movable on the carrier, gearing connecting the holder and frame, and marking means arranged for actuation by a form carried on the support.

27. In an apparatus of the class described, 80 a rotatable carrier, a form holder rotatable on the carrier, a bar pivoted on the carrier, marking means mounted on the bar, and means for contact with a form carried on the support variable in position on the bar with respect to said form.

28. In an apparatus of the class described, 85 a rotatable carrier, a form holder rotatable on the carrier, a bar pivoted on the carrier parallel to the form holder and being provided with a series of depressions, a marking member mounted on the bar, and a member for contact with a form carried on the support movable on the bar and having a latch for engagement with the bar depressions.

29. That improvement in methods of producing co-operating molds which consists in generating an outline of an element of a mold on a section of material and dividing the section along the outline to form corresponding elements of the required co-operating molds.

In testimony whereof I have signed my name to this specification.

THOMAS H. SEELY.
